UNITED STATES PATENT OFFICE.

FRED DIVELBISS, OF STARFIELD, MISSOURI.

WHEEL GUARD OR SHOE.

SPECIFICATION forming part of Letters Patent No. 635,921, dated October 31, 1899.

Application filed June 1, 1899. Serial No. 718,956. (No model.)

To all whom it may concern:

Be it known that I, FRED DIVELBISS, a citizen of the United States, residing at Starfield, in the county of Clinton and State of Missouri, 5 have invented certain new and useful Improvements in Wheel-Guard Shoes; and I do declare the following to be a full, clear, and exact description of the invention, such as will enable others skilled in the art to which it appertains to make and use the same.

My invention relates to improvements in wheel-guards for the carrying or ground wheels of mowers, reapers, and harvesters, and more particularly to that class of analogous attachments of which the device shown 15 in the Letters Patent to Jones and Marshall, No. 365,749, dated June 28, 1887, may be taken as a type; and the object is to simplify and improve the construction and increase the 20 utility and durability of the device.

To this end the invention consists in certain features of construction and combination of parts, which will be hereinafter more particularly described and claimed.

25 In the accompanying drawings the same reference characters indicate the same parts of the invention.

Figure 1 is a perspective view, partly in section, of my improved wheel-guard shoe. Fig. 30 2 is a perspective view of the shoe removed from the machine.

1 denotes the frame, and 2 the bull or traction wheel.

3 represents the guard-shoe, which consists 35 of a sheet-metal plate supported by the braces 4 4, parallel with the frame. This plate is preferably of sheet or steel plate, and it extends on both sides of the wheel and across the front, as shown, the front portion being 40 turned upwardly runner fashion, and the

rear ends are also slightly flared to permit of the wheel being backed.

The lower end portion of the wheel extends a short distance below the shoe, so that in traveling on hard ground the guard-shoe is 45 carried along a short distance above and parallel with the surface of the ground. In soft ground as the wheel sinks a certain distance the broad flat surface of the shoe rides upon the ground and supports the weight of the 50 machine, thus enabling it to pass over boggy places until solid ground is reached.

The accompanying drawings show my invention in the best form now known to me; but many changes in the details might be 55 made within the skill of a good mechanic without departing from the spirit of my invention as set forth in the claim at the end of this specification.

Having thus fully described my invention, 60 what I claim, and desire to secure by Letters Patent, is—

In a machine of the class described, the combination with the horizontal, rectangular frame 1, the ground-wheel 2 mounted within 65 said frame, of the guard-shoe 3 arranged parallel with said frame and open at its rear end, and having its free ends projecting beyond the rear end of said frame to form a guard therefor, substantially as and for the purpose 70 set forth.

In testimony whereof I have hereunto set my hand in presence of two subscribing witnesses.

FRED ^{his} X DIVELBISS.
